CLARENCE D. PLATT, OF BRIDGEPORT, CONNECTICUT

LOCK ATTACHMENT FOR SNAP-SWITCHES.

1,076,907.

Patented Oct. 28, 1913.

Application filed February 12, 1913. Serial No. 747,912.

To all whom it may concern:

Be it known that I, CLARENCE D. PLATT, a citizen of the United States, residing at Bridgeport, county of Fairfield, State of Connecticut, have invented an Improvement in Lock Attachments for Snap-Switches, of which the following is a specification.

This invention relates to electric snap switches and has for one object to provide 10 key-actuated means for operating switches of this character, by which the switch may be easily operated by an authorized person to open or close the circuit, but which will be extremely difficult of operation by unauthorized persons who may be inclined to 15 mischief or malice.

Another object of the invention is to provide an operating device for switches provided with means for engagement by a key, 20 which may be readily substituted for the usual or regular turn-button or handle by which said switches are usually operated, thereby converting an ordinary switch into a lock switch.

25 A further object of the invention is to provide means which will tend to injure the fingers of an unauthorized person who may persist in attempting improperly to operate the switch, thereby discouraging such attempts. This feature of the invention is particularly useful in connection with 30 switches located at points where they are likely to be meddled with by children.

With these and other objects in view I 35 have devised the novel switch operating means which I will now describe, reference being had to the accompanying drawing forming a part of this specification in which—

40 Figure 1 is a side elevation of a switch provided with operating means constructed in accordance with the invention; Fig. 2 is a vertical section thereof; Fig. 3 is a plan view and Fig. 4 an elevation partly in section of the operating means detached; Fig. 5 is a plan view of a modified form of the guard member; Fig. 6 is a plan view of a further modified guard member and a slightly modified form of operating member; Fig. 7 is a detail sectional view of the 45 guard member shown in Fig. 6; Fig. 8 is a detail view of the key employed for actuating the switch.

10 denotes the base and 11 the cover of 50 an ordinary snap switch comprising a switch

blade 12 operated by a spindle 13 to make and break the circuit through contacts 14. The specific form of the switch mechanism forms no part of the present invention and will not be described in detail, but may be 60 of any usual or well known form operated by a spindle similar to the spindle 13 shown in Fig. 2. Said spindle 13 is provided with an outer threaded end to which the regular manually operated turn-button is usually attached.

15 denotes the key-actuated switch operating member forming a part of the present invention and which is adapted for attachment to the switch spindle 13 in substitution for the usual turn-button. To this end said operating member comprises a body portion, provided with an internally threaded shank 16 adapted to be screwed into place on the end of the switch spindle 13. 70 The operating member 15 is preferably round in outline, is formed with a smooth surface so as to be with difficulty turned by the fingers, and, as shown in Fig. 3, is provided with a pair of circular openings 17 75 for engagement by the prongs on a key, such for example, as that shown in Fig. 8.

18 denotes a guard member or disk loosely mounted on the shank 16 and provided with an edge portion surrounding the edge of 80 said operating member. As shown in Figs. 1 to 4, the edge portion of the guard member is formed as a series of outwardly inclined points or angular projections 19. As will be seen, any attempt to grasp and turn 90 the operating member 15 manually will bring the fingers into engagement with the points 19, which will be pressed into and prick the fingers if any considerable pressure upon the operating member is attempted.

20 denotes a spring washer mounted on the shank 16 beneath the guard member 18 and 21 a fiber washer interposed between the spring washer 20 and the switch cover 100 11. The spring washer 20 performs the double function of holding the guard member 18 in close engagement with the operating member 15 and of holding the switch cover 11 in close engagement with the base 105 10. The purpose of the fiber washer 21 is to prevent undue friction between the spring washer and the switch cover. 22 denotes a preferably conical enlargement or head formed on the end of the shank 16, said 110

head being of slightly greater diameter than that of the opening in the fiber washer 21, so that when said fiber washer is forced over said head it will be retained in place on the shank 16 and serve also to retain the spring washer 20 and guard member 18 in assembled position.

In Fig. 5 is shown a modified form of guard member 180 having a series of blunt 10 projections 190 which, while performing substantially the same function as the points 19 on the guard member 18, will not tend to injure the fingers of a person attempting to operate the switch manually.

In Figs. 6 and 7 is shown still another 15 form of guard member provided with a continuous, outwardly inclined flange 191 which, while not tending to injure the fingers of the operator, entirely surrounds the edge of the operating member 151 and prevents the latter from being grasped and turned manually.

As shown in Fig. 6, the operating member 151 is provided with a pair of angular slots 20 corresponding to and serving the same function as a circular opening 17 in the operating member 15.

Having thus described my invention I claim:

1. In a snap switch, the combination with a switch spindle, of an operating member for said spindle provided with means for engagement by a key, and a guard member loosely mounted adjacent said operating member and having a series of points projecting beyond the edge of said operating member.

2. In a snap switch, the combination with a switch spindle, of an operating member for said spindle provided with means for engagement by a key, a guard member loosely mounted adjacent said operating member and having a series of points projecting beyond the edge of said operating member, and means for holding said guard member in close engagement with said operating member.

In testimony whereof I affix my signature in presence of two witnesses.

CLARENCE D. PLATT.
